UNITED STATES PATENT OFFICE

92,386

DESIGN FOR A TOY VEHICLE

Charles C. Blackmore, Oakwood, Ohio

Application March 9, 1934, Serial No. 50,991

Term of patent 7 years

To all whom it may concern:

Be it known that I, CHARLES C. BLACKMORE, a citizen of the United States, and a resident of Oakwood, in the county of Montgomery and State of Ohio, have invented a new, original, and ornamental Design for a Toy Vehicle, of the type commonly known as a Scooter, of which the following is a specification, reference being had to the accompanying drawing, forming a part thereof.

Fig. 1 is a side elevation of a toy vehicle showing my new design, with a portion of the steering handle broken away; and Fig. 2 is a top plan view of the same.

I claim:

The ornamental design for a toy vehicle as shown and described.

In testimony whereof, I affix my signature hereto.

CHARLES C. BLACKMORE.
